(57) **CLAIM**

We claim the ornamental design for front portions of stackable and stacked display bins having pivotal doors, as shown and described.

DESCRIPTION

FIG. 1 is a top, front, and right side perspective view of a first embodiment of a front portions of stackable and stacked display bins having pivotal doors showing our new design; FIG. 2 is a front view thereof;

FIG. 3 is a top plan view thereof;

FIG. 4 is a bottom plan view thereof;

FIG. 5 is a right side view thereof, it being understood that the left side view is a mirror image reversal of the right side view;

FIG. 6 is a top, front, and right side perspective view of a second embodiment of a front portions of stackable and stacked display bins having pivotal doors showing our new design;

FIG. 7 is a front view thereof;

FIG. 8 is a top plan view thereof;

FIG. 9 is a bottom plan view thereof;

FIG. 10 is a right side view thereof, it being understood that the left side view is a mirror image reversal of the right side view;

FIG. 11 is a top, front, and right side perspective view of a third embodiment of a front portions of stackable and stacked display bins having pivotal doors showing our new design;

FIG. 12 is a front view thereof;

FIG. 13 is a top plan view thereof;

FIG. 14 is a bottom plan view thereof; and,

FIG. 15 is a right side view thereof, it being understood that the left side view is a mirror image reversal of the right side view.

The broken-line disclosure of elements of display bins is provided for illustrative purposes only and forms no part of the claimed design forms.
